UNITED STATES PATENT OFFICE.

WALTER F. NEWHOUSE, OF BENTON HARBOR, MICHIGAN, ASSIGNOR TO SARANAC AUTOMATIC MACHINE CORPORATION, OF BENTON HARBOR, MICHIGAN, A CORPORATION OF DELAWARE.

MACHINE FOR MAKING BASKETS.

Application filed February 11, 1924. Serial No. 691,954.

This invention relates to machines for making baskets, and particularly to those for making bushel baskets, or other baskets of different size, but of the same shape and style, and more especially to machines for making baskets of that particular kind in which both the bottom and the top are flat, whereby the product of such machine is a frusto-conical basket structure having inside and outside top and bottom hoops, the inside bottom hoop being of less diameter than the other hoops.

Generally stated, therefore, the object of the invention is to provide machinery for use in the making of frusto-conical baskets, having means for accurately positioning and rotating an inside bottom hoop for the basket, while the side staves are being stapled to such hoop, or to other hoops, this inside bottom hoop being smaller, of course, than the hoops for the upper edge or top of the basket.

Another object is to provide a novel and improved stapling machine for stapling together the hoops and staves forming the sides of the basket, by rotating the said frusto-conical structure about an axis disposed adjacent to the stapling mechanism, said axis preferably extending at an oblique angle, relatively to the staplers, so that the staplers may be arranged conveniently in a row and may operate in unison to simultaneously insert staples in the hoops of the basket, and through the hoops and the staves, thus fastening the hoops in place on the sides of the basket, and whereby the frusto-conical structure is effectively held in place during the stapling operation, and is easily released when completed.

It is also an object to provide certain details and features of construction and combinations tending to increase the efficiency and desirability of a basket stapling machine of this particular character.

To the foregoing and other useful ends, the invention comprises matters hereinafter set forth and claimed, and shown in the accompanying drawings, in which

Figure 1 is a side elevation of a basket stapling machine embodying the principles of the invention.

Figure 2 is a similar view showing the other side of the said machine.

Figure 3 is a front elevation of said machine.

Figure 4 is a rear elevation of said machine.

Figure 5 is an enlarged longitudinal section of the form upon which the basket is made, showing the said frusto-conical structure thereon, on line 5-5 of Figure 1.

Figure 6 is a detail sectional view on line 6-6 in Figure 7, showing a fragment of the form upon which the frusto-conical structure of staves and hoops is built by the attendant or person operating the machine.

Figure 7 is a side elevation of the said form upon which the basket is built.

Figure 8 is a side elevation of the completed frusto-conical structure which is, as it leaves the machine, open at each end thereof.

As thus illustrated, the invention comprises an upright body 1 having a base 2 adapted to rest upon the floor, and having a top portion 3 upon which the stationary head 4 of the stapling mechanism is suitably secured and mounted. The upper or movable stapler head 5 is rigidly secured to the upper end of the vertically disposed rod 6 which is movable up and down in the guide 7 forming a part of the lower stationary head, and in the body 1, whereby the upper head 5 is reciprocated up and down in the desired manner to operate the three staplers 8, which latter are of any suitable known or approved character. The lower end of the rod 6 is connected by a link 9 with a crank 10 on the horizontal shaft 11, which latter is mounted to rotate in bearings 12 and 13 suitably provided for this purpose, whereby said crank is housed in the body 1 of the machine. A loose pulley 14 is mounted on said shaft, and transmission of power from this pulley to the shaft 11 is controlled by the clutch 15, of any suitable character, which in turn is controlled by a foot lever 16 or other suitable means. The said staplers are each provided with a wire feed device 17, of any suitable character, arranged in a row on the horizontal shaft 18, which latter is supported in suitable bearings on

the machine. The upper feeding rolls of the said feed device are mounted on this shaft 18 and this shaft is intermittently rotated to feed the wire to the staplers in the usual well known manner. The intermittent rotation of this shaft is accomplished by a ratchet device 19 at the outer end of the shaft, which ratchet device is operated by a rod 20 leading downward therefrom to the eccentric cam device 21 mounted on the shaft 11 previously mentioned, whereby this rod 20 is reciprocated endwise, in the desired manner, thereby to intermittently rotate or actuate the shaft 18, causing all three feed devices 17 to feed wire at the same time. The length of wire fed by each feed device, of course, is cut off at the proper time, by the staple former of each stapler, and each length of wire is formed into a staple and then driven by a further downward movement of each stapler as the head 5 moves downward, whereby all three staples are formed simultaneously and driven simultaneously in the work, as will hereinafter more fully appear. For the vertical adjustment of the three staplers, screw adjusting devices 22 are provided for the attachment to the upper ends of the staplers to the head 5, as shown, whereby these staplers may be adjusted vertically to insure accurate operation thereof. As stated, the three staplers may be of any suitable known or approved form or construction, and as shown are of a well known form or construction, as will be apparent to those skilled in the art. The wire 23, as shown in Figure 3, is fed through the feed device 17 of each stapler, and into the tube 24 which forms a guide for directing the wire horizontally below each stapler.

The means for supporting the frusto-conical structure shown in Figure 8, during the making thereof, are as follows: The body 1 is formed with a flat face portion 25 to which is detachably secured the face plate 26 in which is rigidly inserted and held an arbor or axis member 27, this member 27 being tilted slightly so that its outer end is higher than its other end, as shown in Figures 1 and 2, so that the axis of this member is at an angle, instead of being disposed horizontally. A rotary form is mounted on this arbor, comprising the discs 28, 29 and 30, which are rigidly secured to the sleeve 31, it being observed that the disc 28 is the largest, while the disc 29 is somewhat smaller, and that the disc 30 is the smallest. A plate 32 is detachably secured to the arbor or axis member 27, to hold the form in position thereon, and the disc 28 is provided with a ratchet ring 33 in the space between this disc and the face plate 26 previously mentioned. The shell 34 of the form is of any suitable character, but is frusto-conical in accordance with the character of the structure to be made, and fits upon the outer beveled peripheries of the discs 28, 29 and 30, in the manner shown. This shell is provided at its larger end with a ring 35, and at its smaller end with a ring 36, rigid therewith, to receive the inner hoops 37 and 38 of the basket, which hoops are first formed and then placed in position on the rings 35 and 36 to receive the staves 39 which are next placed in position on the form. To receive the staves 39, and to hold them in place, rings 40 are provided on the shell and these rings, being channel shaped in cross section, have springs 41 secured therein by rivets 42, with the secured end of each spring bent outward and over to form a stop 43 to limit the outward movement of the next spring. The staves are inserted by hand, in the manner shown in Figure 6, by inserting them edgewise between the springs 41 and their stops 43 so that they will be held as shown. To hold the shell 34 on the form, and to hold the basket materials thereon, locking mechanism is provided as shown in Figure 5, comprising fingers 44 which are pivoted on the disc 30 at 45, and which are of such length and shape that they can swing over the disc 30 to engage the outer edges of the shell 34 and the hoops and staves of the basket structure. These fingers have short ends 46 which are shaped to engage the disc 30, thus forming stops to limit the outward swing of the fingers, as shown in dotted lines in Figure 5, and for the operation of these fingers they are connected with the handle 48 by pivoted links 47. This handle has a stem or rod 49 for insertion in the longitudinal bore 50 formed in the outer end portion of the arbor, previously mentioned, in the manner shown in Figure 5 of the drawings. By grasping the handle 48 and pulling outward thereon, the fingers 44 may be swung outward, so that the shell 34 with the completed frusto-conical basket structure thereon may be removed from the form of the machine. It will be seen that the beveled peripheries of the discs 28, 29 and 30, at their upper edges, are in line with the three staplers 8, so that these discs provide a solid backing below the work to receive the thrust of the staplers, and the staples are clinched on the beveled peripheries of the rings 35 and 36, and the middle ring 51, of the shell upon which the basket is built and stapled. When the handle 48 is pushed inward, the fingers 44 are moved into operative position, and at such time the alignment of the pivots of the links 47 is such that the fingers are locked in this position, and they will remain in this position until the handle is again pulled outward.

Now the outer hoops 52, 53 and 54 of the basket are secured to the staves 37 by staples

55 inserted by the three staplers shown and described, during the rotation of the form. For the rotation of the form in intermittent manner, whereby the work is stationary 60 when the staples are being driven, a ratchet dog 53 is provided on a link 57, the latter being pivoted at 58 on the body frame, and said ratchet dog being adapted to engage the ratchet teeth of said ratchet ring 33 previously mentioned. The other end of the link 57 is connected by a rod 59 with the upper head 5 of the stapling mechanism, whereby the up and down movement of this head causes an endwise reciprocation of the rod 59, and consequent up and down movement of the link 57, which in turn will cause the ratchet ring 33 to be intermittently rotated. Thus, each time the staplers rise, the rod 59 moves upward, just after three staples have been driven by the three staplers, and such upward movement causes the ratchet dog 56 to rotate the ring 33 and the basket form in the desired manner, causing new places in the work to be brought into position to receive the next set of staples, the machine driving three staples, one in each hoop of the basket, each time the upper head of the stapling mechanism moves downward. The hoops 52, 53 and 54 are fed, respectively, through the guides 60, 61 and 62 to their positions below the three staplers, so that the straight strips from which the hoops are to be formed, when thus inserted with their ends below the staplers, will receive the first staples to be driven in the work. Of course, as soon as the hoop strips are attached by these first staplers, to the staves of the basket, and to the inside hoops of the basket, the rotation of the basket form will automatically feed the hoop strips from the guides 60, 61 and 62 until they are wound entirely around the basket and finally secured in place with their ends overlapping, in the desired manner. The said guides are pivotally hung on a horizontally disposed axis member 63, which latter is supported by lugs 64 cast on the front plate 65 to the lower head of the stapling mechanism. Thus these hoop guides are adapted to tilt about a horizontal axis, when the inserted ends of the hoop strips are pressed downward by the staplers, during the insertion of the first staples. Thus, when the hoop strips are first inserted, their end portions are close up against the lower ends of the staplers, to receive the points of the staples, the outer end of each guide being enlarged to facilitate insertion of the hoop strip therein. The inner ends of the hoop guides are held normally raised, but yieldingly so, by the springs 66 which latter have their upper ends attached to any suitable supporting means on the plate 65, and have their lower ends suitably attached to the hoop guides, whereby the inner ends of the guides are yieldingly held in raised position, as shown, but are adapted to be depressed to allow the inserted end portions of the hoop strips to be pressed downward by the staplers and secured to the staves of the basket structure.

It will be seen that the work holding shell 34 is provided with hooks 67 to engage in notches 68 provided on the tapered form, to lock the shell in place on the form. The tapered form is removable, of course, by removing the plate 32, but this can only be done when the stapling mechanism is out of the way or is not in operative position, for axial displacement of the form is not possible while the stapling mechanism is in operative position, inasmuch as the disk 29 would strike the lower end of the outer stapler, while the disk 28 would strike the lower end of the inner stapler. However, notwithstanding the frusto-conical formation or taper of the finished receptacle, the displacement thereof is facilitated and made possible by the shell 34, inasmuch as this shell can slide horizontally upon the top of the tapered form, thus producing endwise and partially downward movement of the receptacle, resulting in a displacement of the receptacle in a direction at an angle to the axis of the form. Thus the top of the form is in a horizontal plane, the lower ends of the staplers are in a horizontal plane immediately above, and the upper side of the basket is maintained in a horizontal plane between the form and the lower ends of the staplers. When the basket is displaced from the form, on the removable shell, the upper side of the basket moves outwardly in the horizontal plane thereof, so that the lower side of the shell 34 is immediately separated from the lower side of the tapered form, thereby facilitating easy removal of the shell and the finished basket thereon. Because of the taper of the basket, and because of the position of the staplers, axial displacement of the basket, or displacement of the basket in the direction of the axis of the form, is precluded, for the staplers are in such position that axial displacement of the basket or the shell, or the form, is not possible while the staplers are in operative position. However, means are provided, preferably in the form of a shell 34 having the work holding devices thereon, to permit displacement of the finished basket in a direction at an angle to the axis of the form, by movement of the basket and shell horizontally, because of the position of the form, so that the upper side of the basket moves in the plane thereof and in a direction parallel with the bottom of the stapling mechanism. Of course, said shell 34 can be made of any suitable or desired materials, such as thin sheet metal, or aluminum.

num, in order that the shell may be light and easy to handle. The shell may be used in any suitable or desired manner, as by placing it on a bench and inserting the 5 staves 39 between the springs 41 and the stops 43, in the manner indicated, and the shell after being thus loaded can be placed on the form and locked thereon in the manner shown. It will be seen that the staves have 10 substantially the same width at each end thereof, as indicated by the dotted lines in Fig. 8, so that these staves overlap each other to a greater extent at the smaller end of the basket than at the larger end thereof. 15 Again, it will be seen that the staples are inserted in such a manner that the same number of staples will be inserted in each hoop, preferably through the overlapping portions of the staves, but the staples in 20 the hoop 54 will be closer together than those in the hoop 53, and the staples of the latter hoop will be closer together than the staples of the hoop 52, because of the fact that the hoops are of different diameters. The 25 staplers will drive three staples in a row lengthwise of the basket, each time the stapling mechanism is operated, but the staples in the circular rows encircling the basket will not be driven the same distance apart in each 30 row, for those in the smaller hoop will necessarily be closer together than those in one of the larger hoops.

The method employed therefore involves the arrangement of staves in overlapping relation, so that one longitudinal edge of each 35 stave is covered while its other edge is exposed between the hoops or other encircling members on the outer surface of the basket, and the applying of encircling reinforcing members to the outer surface of the staves thus assembled in overlapping relation. Preferably the encircling members are 40 hoops, and are held in place by staples, and preferably the application of these encircling members takes place at a time when the 45 smaller and the larger ends of the receptacle are still open, whereby the immediate product of this stapling operation is a frustoconical body having both ends thereof left 50 open.

It will be understood, of course, that the product thus made, as shown in Fig. 8, can be used in any suitable or desired manner, as by subsequently providing it with suitable handles and by providing it with end 55 walls for the smaller and larger ends thereof, in any suitable or desired manner. Therefore the machine is of a novel character, and the method employed, regardless 60 of what apparatus is employed for practicing the method, is also characterized by some novelty, because distinguished from prior methods of assembling materials to form baskets or receptacles. Of course, the

method involves the formation of the hoops 65 37 and 38 first, the assembling of the staves thereon, and the subsequent application of the encircling members 52, 53 and 54 to the outer surface of the basket in the manner explained. In other words, the inner hoops 70 37, 38 must be made first and placed on the shell 34, and then the staves 39 are assembled in overlapping relation upon the outer surface of the shell 34, and thereafter by rotation of the form and the shell with the 75 materials thereon, the machine shown and described is rendered operative to insert the staples 55 to secure the hoop strips 52, 53 and 54 in place, and to gradually wind these strips around the basket, thus forming the 80 outside hoops of the basket.

Thus the staple clinching rings 35 and 36 form means also for positioning top and bottom inside hoops for the basket, so that the staves may be fastened thereto, with the staples extending through the outer hoops also, as shown and described. The hoop positioning means, therefore, are removable from the form, from the smaller end of the frusto-conical form, with the basket, in the manner explained. As the staples 55 are inserted through the overlapping portions of the staves, it follows that the shell must be properly positioned on the form, as is done by the portions 67, and that the stapling operations must be performed in timed relation to the feeding movements and the points of overlap of the staves. In other words, as many staples are driven in each outside hoop as there are staves, there being one staple in each hoop for each stave, and each staple being inserted in the overlapping portions of the staves, thereby forming a strong basket with tight side walls. 100 Thus the means for positioning the inside hoops are removable from the form, and the means for positioning the staves are removable from the form, with the basket, in the manner explained, thus not only facilitating the removal of the basket when finished, but also the assembling of the materials on the shell for the next basket, as it can be placed on a bench or table and conveniently loaded with the inside hoops and the staves 105 for each basket. When the loaded shell is placed on the form, the hooks 67 pass through the notches 68, and a slight rotation of the shell then interlocks the hooks with said notches, thereby preventing displacement of the shell on the form during the rotation thereof. When the basket is finished, the handle 48 is pulled outwardly, the shell is given a slight turn to disengage the hooks 67 from the notches 68, and the shell then slides off easily in the manner explained. Then a slight turn or twist of the shell in the basket, to disengage the portions 43 from the edges of the staves, is sufficient 110 115 120 125

to permit removal of the shell from the finished basket.

While the method shown and described results in the production of a basket which is open at the top and bottom thereof, it is obvious that any suitable or desired form of basket, having inner and outer top and bottom hoops, and having uniformly overlapping staves, with staples inserted through the inner and outer hoops and through the overlapping portions of the staves, can be made by the method and machinery shown and described, without departing from the spirit of the invention, the uniform overlapping of the staves, in the assembling thereof, to form a frusto-conical basket, and the provision of means for suitably incorporating an inner bottom hoop which can be used as a shoulder upon which to support the bottom wall of the basket, being essential.

It will be seen that the inside bottom hoop supporting means 36 is flanged to form a portion to engage the upper edge of the inside bottom hoop, to correctly position the hoop in the machine. Furthermore, it will be seen that the inside bottom hoop supporting means is movable away from the machine, in a direction away from the stapling position of the top of the basket, and in a direction away from the basket form that supports the staves and the other hoops of the basket, thereby to facilitate removal of the basket from the machine. Means are provided for holding the inside bottom hoop against displacement and for holding the inside bottom hoop supporting means in operative relation to the basket form, during the stapling operation, but said means are operable to permit movement of the bottom hoop support away from the form, in the manner shown and described, or in any suitable or desired manner, to facilitate the removal of the basket from the machine. However, and notwithstanding that the inside bottom hoop support is movable away from the basket form, the said support and form are held against relative rotation, and are rotated in unison, during the stapling operation.

The hoops of the basket are ordinary hoops, as shown, being cylindrical, and for this reason the rings 35 and 36 are provided with cylindrical surfaces to engage the inner cylindrical surfaces of the top and bottom inside hoops. Similarly, the ring 51 has a cylindrical outer surface, as the hoop 53 is cylindrical, notwithstanding the downward taper of the basket, the side wall staves being inclined outwardly as shown. The means for thus supporting the inside hoops in position to have the staves stapled thereto, are held against axial movement, during the rotation of the work supporting means, so that

the staples 55 at the bottom of the basket are all in the same plane, and this is also true of the staples for the hoop 53 and those for the hoops 37 and 52, so that the staples are all in three straight parallel planes extending at right angles to the axis of the rotary work supporting means. The ring 36, being mounted for rotation, forms a rotary means for accurately positioning and holding the inside bottom hoop 38, relatively to the stapler immediately above, and relatively to the staves and other hoops of the basket. The hoop supporting means is held against axial movement, during its rotation, serving thereby to support and hold the hoop in position against axial displacement or movement during the rotation thereof, so that the staples are all in one plane.

What I claim as my invention is:

1. In a machine for making receptacles, the combination of work supporting means having provision for relatively positioning and holding the uniformly overlapping staves of a frusto-conical receptacle or basket in position to be fastened together, and stapling mechanism for stapling a plurality of inner and outer hoops of different diameters to said receptacle to reinforce the walls thereof, including means to position an inside bottom hoop for the smaller end of the downwardly tapered basket, in combination with devices to rotate said work supporting means, with each hoop in position to receive a series of staples therein, relatively timed to insert the staples through the overlap of the staves.

2. A structure as specified in claim 1, said work supporting means comprising a rotatable body, and a removable shell on said body, which shell is provided with devices for receiving and holding the materials of the receptacle in position to have said hoops stapled thereto.

3. A structure as specified in claim 1, said work supporting means comprising a tapered form, a tapered shell removably mounted on said form and carrying the work holding and positioning means, the axis of said form being disposed at an angle, whereby the smaller end of the receptacle is tilted upward so that the upper side of the receptacle is maintained in a horizontal plane during the stapling of the hoops thereto, and said shell being removable endwise while the upper side thereof is maintained in the horizontal plane thereof, said stapling mechanism comprising a plurality of staplers disposed in a row immediately above the horizontal plane of the upper side of the receptacle, and said removable shell thus facilitating the removal of the tapered receptacle from below said staplers, small end first, from the said form.

4. In a machine for making receptacles, the combination of a tapered form, a tapered

- removable shell on said form, devices on said shell to receive the uniformly overlapping staves for the receptacle, so that the shell may be loaded and then placed on the 5 form, a stapling mechanism for operating upon the materials to fasten them together, and devices to rotate said form, relatively timed to insert the staples through the overlap of the staves, said removable shell facilitating the removal of the tapered receptacle by keeping one side thereof parallel with the 10 stapling mechanism, the relative arrangement being such that axial displacement of the finished receptacle is precluded by the 15 position of said mechanism.
5. A structure as specified in claim 4, said mechanism comprising a plurality of staplers arranged in a row, means for guiding a hoop below each stapler to be stapled to the receptacle, whereby the hoops are of different diameters, interlocking means to relatively position the shell on the form to properly present the work to said staplers, and means for operating said staplers simultaneously, 20 whereby the same number of staples will be driven in each hoop, but with the staples in a smaller hoop driven closer together than those in a larger hoop.
6. A structure as specified in claim 4, said mechanism comprising a plurality of staplers arranged in a row, with one end of the row at the smaller end of the receptacle and the other end of the row at the larger end of the receptacle, interlocking means to relatively 25 position the shell on the form to properly present the work to said staplers, and whereby rotation of the receptacle results in the driving of a plurality of circular rows of staples therein, having the same number of 30 staples in each circular row, but with the staples in the circular row at the smaller end of the receptacle disposed more closely together than are those in the circular row of staples at the larger end of the receptacle.
- 40 7. A structure as specified in claim 4, said tapered form having locking devices for engaging the smaller end of the shell and the receptacle, adapted by manual operation to permit endwise removal of the shell with the receptacle thereon.
- 45 8. In a machine for making receptacles, the combination of a rotary frusto-conical form rotatable about a fixed axis, adapted to support uniformly the overlapping staves 50 of a frusto-conical receptacle thereon, fastening mechanism to operate upon the receptacle, disposed in position to preclude axial displacement of the receptacle when finished, relatively timed to insert the fasteners 55 through the overlap of the staves, and instrumentalities to permit displacement of the finished receptacle without hindrance by said mechanism.
- 60 9. A structure as specified in claim 8, said instrumentalities comprising a tapered shell on said frusto-conical form, between the form and the receptacle, having means to engage the receptacle, which shell is adapted to slide upon one side of the tapered form while being displaced with the finished 65 receptacle thereon, and is thereafter removable from the receptacle.
10. A structure as specified in claim 8, said mechanism comprising a plurality of staplers disposed in position to simultaneously drive 70 a plurality of staples in a row extending lengthwise of the receptacle, and said instrumentalities comprising means interposed between the form and the receptacle, adapted for endwise displacement with the finished 75 receptacle thereon, by movement of the receptacle at an angle to the axis of said form.
11. A machine for making frusto-conical baskets, comprising a suitable form having means adapted for holding and positioning uniformly overlapping straight staves, with means for positioning an inner relatively large top hoop and an inner relatively small bottom hoop for the basket, upon which the ends of said staves overlap when the materials are in position on the form, means for feeding outer top and bottom hoop strips, to the outer surface of the staves, and also one centrally located outside hoop strip, and mechanism disposed in position for forming 85 and driving staples through the outer hoops and through the overlapping portions of the staves into the said inner hoops.
12. In a machine for making frusto-conical baskets, the combination of a frusto-conical rotary form having means thereon to position top and bottom inside hoops for the basket, with the smaller hoop in the bottom of the basket, means on said form to position staves in overlapping relation on 90 said hoops, means to apply outside hoops to the basket, means to insert staples through said hoops and staves, said hoop positioning means serving also to clinch the staples, and means to rotate said form in timed relation 95 to said stapling means.
13. A structure as specified in claim 12, said means for positioning the inside bottom hoop of the basket being displaceable from the form with the basket.
14. A structure as specified in claim 12, said means for positioning the inside bottom hoop of the basket and also the inside top hoop, being both displaceable from the smaller end of the form with the basket, and being then removable from the basket.
15. A structure as specified in claim 12, said means for positioning the inside bottom hoop of the basket being removable from the smaller end of the form, and means to lock 125 said hoop positioning means against relative rotation on the form.
16. The combination of a frusto-conical basket form to receive the basket materials, removable means on the smaller end of the 130

- form to position an inside bottom hoop for the basket, means whereby said hoop positioning means is locked against relative rotation on the form, but is removable therewith from the basket, means to rotate the form, and means to insert staples through the materials and through said inside bottom hoop.
17. In a machine for use in making baskets, the combination of rotary means adapted and disposed in position for supporting and accurately positioning an inside annular bottom hoop for the basket, and in position to have the converging lower ends of outwardly inclined side wall staves stapled to the annular outer surface thereof, and mechanism adapted and disposed in position for driving staples through the staves into said hoop, as the hoop is rotated in the plane thereof, said hoop positioning means being held against axial movement during its rotation, thereby serving to hold the hoop against axial displacement or movement relatively to said mechanism, during the rotation thereof, whereby the staples are all in one plane.
18. A structure as specified in claim 17, comprising means for supporting an inside top hoop for the basket, and mechanism for stapling the other ends of said staves to said top hoop, together with means to feed hoop strips to form top and bottom outside hoops, said mechanism being operative to drive said staples through the outside hoops and through the staves and inside hoops, said hoop supporting means being cylindrical to engage the cylindrical inner surface of each hoop and adapted to clinch the inner ends of the staples.
19. A structure as specified in claim 17, said hoop supporting means being rotatable relatively to said mechanism, having a portion to engage one edge of the hoop, and serving to clinch the inner ends of the staples on the inner side of the hoop, and means to hold said hoop supporting means against axial displacement while being rotated.
20. A structure as specified in claim 17, said hoop supporting means being displaceable outwardly from the machine, from under said mechanism, to permit removal of the work from the machine.
21. A structure as specified in claim 17, in combination with means for feeding a hoop strip over said staves to form an outside bottom hoop attached by staples to said inner bottom hoop.
22. A structure as specified in claim 17, said hoop supporting means being movable away from the operative position thereof in the direction of removal of the basket to permit removal of the basket from the machine.
23. A structure as specified in claim 17, in combination with annular means for supporting said staves intermediate the ends thereof, means to feed a hoop strip over the staves in the plane of said annular means, and mechanism to insert staples through said hoop strip and staves, causing the staples to clinch on the inner surface of the staves a distance from said inside bottom hoop.
24. A structure as specified in claim 17, said hoop supporting means being movable in a direction away from the stapling position of the top of the basket to permit removal of the basket from the machine, and means to hold said hoop supporting means in operative position during the stapling operation.
25. A structure as specified in claim 17, comprising a basket form to support the staves, said hoop supporting means being movable away from the form to permit removal of the basket from the machine.
26. A structure as specified in claim 17, comprising a basket form to support the staves, said hoop supporting means being movable away from the form to permit removal of the basket, and means to hold said hoop supporting means in operative relation to the form.
27. A structure as specified in claim 17, comprising a basket form to support the staves, having means to position and support an inside top hoop for the basket, said bottom hoop supporting means being movable away from said form to permit removal of the basket, means to hold said bottom hoop supporting means in operative relation to said form, during the stapling operation, means for rotating the form and thereby rotating the bottom hoop supporting means, by power communicated through the form to said bottom hoop supporting means, devices to feed outside top and bottom hoop strips to the staves, and mechanism to drive staples through the top hoop strip and through the staves and through the inside top hoop.
28. A structure as specified in claim 17, in combination with positioning means engaging the bottom edges of the basket structure, rotatable in unison with said rotary means.
29. In a machine for use in making baskets having annular hoops, the combination of rotary engaging means adapted and disposed in position for engaging and supporting an inside annular bottom hoop for the basket, with the converging end portions of staves and an outside bottom hoop thereon, stapling mechanism for inserting staples through the basket structure during the intermittent rotation thereof, said rotary means being held against axial movement during its rotation, serving thereby to hold the hoop and staves against axial displacement.

ment or movement relatively to the stapling mechanism, during the rotation thereof.

30. A structure as specified in claim 30, said inside bottom hoop engaging means being displaceable after rotation thereof to permit removal of the basket structure from the machine.

31. A structure as specified in claim 30,

said inside bottom hoop engaging means having an annular periphery engaging the 10 inner circumference of said inside bottom hoop, adapted to rotate in the plane of the hoop, and movable horizontally to permit removal of the basket structure from the machine.

WALTER F. NEWHOUSE:

ment or movement relatively to the stapling mechanism, during the rotation thereof.

30. A structure as specified in claim 30, said inside bottom hoop engaging means being displaceable after rotation thereof to permit removal of the basket structure from the machine.

31. A structure as specified in claim 30,

said inside bottom hoop engaging means having an annular periphery engaging the inner circumference of said inside bottom hoop, adapted to rotate in the plane of the hoop, and movable horizontally to permit removal of the basket structure from the machine.

WALTER F. NEWHOUSE:

CERTIFICATE OF CORRECTION.

Patent No. 1,643,287.

Granted September 20, 1927, to

WALTER F. NEWHOUSE.

It is hereby certified that error appears in the printed specification of the above numbered patent requiring correction as follows: Page 8, lines 3 and 8, claims 30 and 31 respectively, for the numeral "30" read "29"; and that the said Letters Patent should be read with this correction therein that the same may conform to the record of the case in the Patent Office.

Signed and sealed this 11th day of October, A. D. 1927.

Seal.

M. J. Moore,
Acting Commissioner of Patents.
